CLAIM

The ornamental design for a warmer, as shown and described.

DESCRIPTION

FIG. 1 is an isometric view of a top, front, and left side of a warmer showing our new ornamental design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dash-dash broken lines are included for the purpose of illustrating portions of the warmer that form no part of the claimed design. The dot-dash broken lines are included for the purposes of illustrating a boundary line that forms no part of the claimed design.
